UNITED STATES PATENT OFFICE

109,615

DESIGN FOR A DOUGH MIXER

Edward J. Lauterbur, Sidney, Ohio, assignor to Peerless Bread Machinery Corporation, Sidney,
Ohio, a corporation of Ohio

Application February 25, 1937, Serial No. 67,859

Term of patent 14 years

To all whom it may concern:

Be it known that I, Edward J. Lauterbur, a citizen of the United States, residing in Sidney, in the county of Shelby and State of Ohio, have invented a new, original, and ornamental Design for a Dough Mixer, of which the following is a specification, reference being had to the accompanying drawing, forming part thereof.

In the drawing:

Fig. 2 is a rear view thereof.

I claim:

The ornamental design for a dough mixer, as shown.

EDWARD J. LAUTERBUR.
